UNITED STATES PATENT OFFICE.

CHARLES F. KINDT, OF JENKINTOWN, PENNSYLVANIA.

TRANSFER FOR LOOSE-LEAF BINDINGS.

1,276,931.

Specification of Letters Patent. Patented Aug. 27, 1918.

Application filed March 22, 1918. Serial No. 223,942.

To all whom it may concern:

Be it known that I, CHARLES F. KINDT, a citizen of the United States, residing at Jenkintown, in the county of Montgomery and State of Pennsylvania, have invented a certain new and useful Transfer for Loose-Leaf Bindings, of which the following is a specification.

The principal objects of the present invention are, first, to facilitate the operation of inserting or removing one or more pages into or from any part of a book having a loose-leaf binding, and second, to provide not only for this but also for the insertion 15 of a greatly increased number of pages. Other objects of the invention will appear from the following description which will be given in connection with the accompanying drawings illustrating an embodiment of 20 the invention and in which—

Figure 1, is a view of a book with front cover laid back showing the lining sheet of a loose leaf binding embodying features of the invention.

Fig. 2, is a sectional view taken on the line 2—2 of Fig. 1.

Fig. 3, is a view showing the back bone or shelf back of the book.

Fig. 4, is a perspective view, and

Fig. 5, is a view of one of the pages or leaves.

In the drawings 1, generally, indicates the transfer, essentially it is detachable and removable from the book and its binding, and 35 it consists of two parallel posts 2, carried by a rigid strip or bar 3. The strip or bar is shown as provided with a lining sheet 4, which adds an attractive appearance to the book. The bar and lining sheet 4, are shown 40 as provided with holes 5, for the reception of the means by which they are detachably connected to the book.

The transfer is useful in connection with loose-leaf binders of which there are many 45 types so that in selecting one type for the sake of further description I do not intend to imply that my transfer is not useful with other types, for it is.

6, are pins, or their equivalents, projecting from a short leaf 7, hingedly attached to one side of the back 8, and adapted for connection to a short leaf 9, hingedly attached to the other side of the back, for example, by means of screws 10, or other well 55 known means.

Having thus described the features of one well known type of loose-leaf binder I will proceed with a description of my transfer in connection with that type of loose-leaf binder, repeating that my invention is not limited to it.

Each sheet 11, is provided with holes 12, for the pins 6, and with holes 13, for the posts 2, which may be of substantially the same length as the pins 6, and the book may be bound up by passing the posts and pins through the proper holes. This brings the transfer, and lining sheet when present, inside of the front cover and at the beginning of the leaves with the short leaf 9, and fastenings 10, exposed on top of it, but with the posts 2, extending into the leaves. To remove or insert pages, the fastenings 10, are removed or released in the usual manner, and then the transfer 1, is lifted bodily 70 with as many pages as may be required on its posts 2, so that these pages are lifted off the pins 6, but remain on the posts 2. The transfer, thus detached from the book, may be inverted and laid down, its posts preserving the alinement of the pages lifted off with it, while the pins 6 preserve the alinement of any pages which may have been left in the binding. Thus pages or leaves 75 may be readily inserted or removed, and it is very easy to return the transfer and the pages which it carries, for the pins and posts can be moved in alinement without any relative turning movement. The fact that the pins and posts move in alinement is additionally important because it permits of the insertion of pages to the full capacity of the binding and it also permits of the pins and posts being of substantially the same length.

It will be obvious to those skilled in the art that modifications may be made in details of construction and arrangement, hence my invention is not limited as to those matters or in any way other than the prior state of the art and the appended claim may require.

What I claim is:

A transfer for loose-leaf binders comprising a rigid strip or bar provided with parallel posts and with a lining sheet and with pin-receiving openings, substantially as described.

C. F. KINDT.
